Primary Examiner — Leanne Was-Englehart(74) *Attorney, Agent, or Firm* — Kunzler Bean & Adamson(57) **CLAIM**

The ornamental design for a crossbody sling, as shown and described.

DESCRIPTION

FIG. 1 is a front view of a crossbody sling;

FIG. 2 is a rear view of the crossbody sling;

FIG. 3 is a left view of the crossbody sling;

FIG. 4 is a right view of the crossbody sling;

FIG. 5 is a top view of the crossbody sling; and,

FIG. 6 is a bottom view of the crossbody sling.

The broken lines in the drawings depict portions of the crossbody sling that form no part of the claimed design.

1 Claim, 6 Drawing Sheets(56)
